UNITED STATES PATENT OFFICE.

EDGAR E. JAMESON, OF SUNNY SIDE, MISSISSIPPI.

CAR-SEAL.

1,102,512.

Specification of Letters Patent.

Patented July 7, 1914.

Application filed December 19, 1913. Serial No. 807,715.

To all whom it may concern:

Be it known that I, EDGAR E. JAMESON, a citizen of the United States, residing at Sunny Side, in the county of Leflore, State of Mississippi, have invented certain new and useful Improvements in Car-Seals; and I do hereby declare the following to be a full, clear, and exact description of the invention, such as will enable others skilled in the art to which it appertains to make and use the same.

The present invention relates to seals, and has particular application to an article of this class adapted especially for use in sealing car doors, and the like.

In carrying out my invention it is my purpose to provide a car seal which is formed of a single blank of metal, and which may be applied in sealing position without the necessity of employing special tools, the seal being manipulated by hand. Furthermore, when once my seal has been applied in sealing position, it is impossible to open or remove the same without destroying it by breaking or cutting the same.

A further object of my invention is the provision of a car seal which will embody the desired features of simplicity, efficiency, and safety, and which may be manufactured and marketed in quantities at a relatively low cost.

With the above recited objects and others of a similar nature in view, my invention consists in the construction, combination and arrangement of parts set forth in and falling within the scope of the appended claim.

In the accompanying drawings: Figure 1 is a perspective view of a seal embodying my invention. Fig. 2 is a plan view of the blank from which the seal is made, the dotted lines indicating the lines on which the folds are made. Fig. 3 is a similar view of the blank showing one side folded. Fig. 4 is a longitudinal sectional view taken through the complete seal as shown in Fig. 1.

Referring now to the accompanying drawings in detail, the numeral 1 designates a blank formed of metal and comprising a strip 2, one end of which has an aperture 3 therein, while the opposite end is cut to form the enlarged rectangular plate 4. This plate 4 has formed integral therewith a tongue 5, formed by making the longitudinal slit 6 adjacent one side edge of the plate,

this slit 6 extending from the free end of the plate to a point beyond the transverse central line thereof. As will be seen by reference to Fig. 1, this free end 7 of the tongue 5 extends beyond the free end of the plate 4, and the portion 8 of the tongue is wider than the shank portion thereof or that portion which connects the tongue with the plate, such wider portion being slotted as at 10, to form the spur 11 which is designed to be bent slightly to one side to form a catch, as hereinafter described, the spur being projected opposite to the direction of projection of the tongue 5. The plate 4 is designed to be folded or bent to form the casing of the seal, and in making the casing in the construction of the seal, the side portions of plate 4 are folded inwardly along the longitudinally dotted lines 12 and 13, as shown in Fig. 1.

Before folding the blank along the line 12, the tongue adjacent its point of connection with the plate 4, is bent transversely to form the double or sigmoidal fold 14 and 80 the spur 11 is bent slightly outward, this spur projecting in a direction opposite to the double fold. After the side of the blank carrying the tongue has been folded inward along the line 12, the opposite side portion 85 of the blank is folded over along the line 13, and sealed or soldered as indicated at 15, it being, of course, understood that there is sufficient passage formed through the casing to permit the free or perforated end 90 portion of the strip 2 to be slipped through the casing beneath the tongue and the portion of the plate carrying the same.

The above is a description of the construction of my seal and the manner of applying the same to the car will be readily apparent. In the application to the car the strip 2 is run through the staples, rings or other securing attachments on the car, and the end portions of the strip having the 100 aperture or slot 3 therein is slipped into and through the casing until the aperture of the strip projects beyond the free end of the casing. It will be noted that the tip end of the tongue 5 which projects beyond the free 105 end of the casing is bent slightly to one side, and when the apertured end of the strip has been slipped through the casing beneath the tongue, such tongue is guided by the bent end 16 thereof through the aperture. The strip is then pulled downward 110 to draw the apertured end thereof into the

casing and over the tongue, until the wall 17 of the slot 3 bears against the bottom of the section 18 of the double fold 14, when the end of the loop or strip will be locked 5 in the casing, for it will be noted that should an attempt be made to push the free or apertured end of the strip out again, it will pass beneath the spur 11 and be caught thereby, while likewise the free or apertured 10 end of the strip cannot be drawn through the casing, for it will be caught by the double fold 14.

It will thus be seen that I have provided an exceedingly simple, yet efficient form 15 of car seal which is cut from a single blank of metal, and which when applied to a car in sealing position, cannot be removed therefrom without destroying, breaking or otherwise injuring the seal, and thereby making 20 it evident that someone has tampered with such seal.

What I claim is:

A seal comprising a strip having an aperture formed adjacent one end thereof, and a widened section formed at the opposite 25 end thereof, said widened section having the opposite longitudinal portions thereof bent inward upon the body of such section to form a casing, one of said bent portions having a relatively long tongue formed 30 therewith, said tongue having a transverse fold adjacent one end, a spur projecting in a direction opposite to the mouth of the fold, said tongue being adapted to pass through the opening in the strip when in sealing po- 35

In testimony whereof, I affix my signature, in the presence of two witnesses.

EDGAR E. JAMESON.
